UNITED STATES PATENT OFFICE.

EDWIN TAYLOR, OF EDWARDSVILLE, KANSAS.

SACK HOLDER.

Application filed January 9, 1922. Serial No. 527,890.

To all whom it may concern:

Be it known that I, EDWIN TAYLOR, a citizen of the United States, and resident of Edwardsville, county of Wyandotte, State of Kansas, have invented a certain new and useful Improvement in Sack Holders, of which the following is a complete specification.

This invention relates to sack holders of that class for supporting sacks in upright opened condition to facilitate the deposit therein of potatoes or other vegetables or things, and the object of the invention is to provide an efficient device of the nature specified, having prongs for quick, easy and positive engagement with and disengagement from the sacks at the mouth end thereof, and for holding each sack so that the weight of the contents shall rest mainly upon ground to avoid the possibility of tearing the sack.

A further object is to provide a support for yieldingly holding an empty sack slightly off the ground and susceptible of lowering the sack when partly filled, to the ground and then holding the unfilled portion of the sack stretched or taut to facilitate the completion of the filling operation.

Another object is to provide a sack holding expandible hopper adapted for suspension from fixed or movable supports.

With these and other objects in view, the invention consists in certain novel and useful features of construction and combinations of parts as hereinafter described and claimed and in order that it may be fully understood, reference is to be had to the accompanying drawings, in which:

Figure 1 is a front elevation of the invention in its preferred type of construction;

Figure 2 is a side elevation of the same;

Figure 3 is a rear elevation of the same;

Figure 4 is a front elevation of a part of the invention in which the hopper member is carried by a fixed but portable support;

Figure 5 is an enlarged vertical section taken on the line V—V of Figure 3, but showing the invention in fragmental form;

Figure 6 is an enlarged horizontal section taken on the line VI—VI of Figure 1;

Figure 7 is an enlarged front elevation of

the hopper member of the device as equipped with auxiliary ends for reducing the length of the discharge portion of the hopper, said figure also showing a portion of a portable support for the hopper;

Figure 8 is a horizontal section of the hopper taken in about the same plane as Figure 6, but showing the equipment for expanding the width of the hopper and for operating the sack holding elements; and

Figure 9 is a detail perspective view of one of the auxiliary end portions of the hopper shown in Figure 7.

Referring now to the drawings in detail, and particularly to the hopper member of the device, 1 indicates the back of the hopper, the same being disposed vertically, and 2 the ends of the hopper, the said ends converging downwardly and having flanges 3 fitting against the back and secured rigidly thereto by fastening devices 4. At the lower ends of the ends 2, are provided horizontal flanges 5 through which pivot hooks 6 extend downwardly, nuts 7 retaining said hooks in position for the support of one of a pair of parallel bars 8, provided at their outer sides with prongs 9 upon which sacks or bags are adapted to be impaled for support in operative position.

The hopper as thus far described, is adapted for supporting sacks for the reception of potatoes and other small vegetables or objects, and means are provided as hereinafter explained, for rocking said prong-carrying bars 8 upwardly and outwardly for the purpose of causing said prongs to impale the sacks for their support. For expanding the width of the hopper for the accommodation of cabbage sacks and other large containers, bars 10 are fitted against the under side of the flanges 5 and fastened rigidly thereto by fastening devices 11 so as to constitute extensions for said flanges 5, to which extensions, when employed, the pivot hooks 6 are transferred so that the front prong-equipped bar 8 can thus be disposed a greater distance from the rear or companion prong-equipped bar 8, as shown clearly by Figure 8, the preferred method of supporting said

last-named bar 8 being by means of hooks 12 secured to the front face of the back of

the hopper, as shown most clearly by Figure 5.

An angle bar 13 is secured horizontally to the upper end and outer side of one of the hopper ends 2, and pivotally suspended from one or more eye bolts 14 carried by said angle bar 13, is a lever 15 provided with a cam plate 16, the cam ends 17 of said plate being adapted when the lever is swung toward the hopper, to engage the end of the bars 8 and swing the same upwardly and outwardly to cause their prongs to assume an angular position for properly retaining a sack in operative position. Reverse movement of said lever withdraws the cam plate or wedge from between said bars and permits them to swing back to a vertically pendant position and release the sack. It will be noticed by reference to Figure 8 that at one end the cam plate or wedge 16 is provided with a cam surface 18 formed by producing a notch in the plate, this cam surface 18 cooperating with the rear cam end 17 in the operation of the bars 8 in the event it is desired to reduce the width of the hopper by setting the front bar 8 in line with the cam surface 18, it being noted by reference to the last mentioned figure that the flanges 5 are provided with a series of holes to permit of adjustment of the hooks 6 in line with the cam surface 18 or the front cam end 17, certain of said holes being also utilized for engagement by the fastening devices 11 when the extension 10 are employed to dispose the front bar 8 at a greater distance from the back wall of the hopper than is possible when the hooks 6 are suspended directly from the flanges 5. In the latter event, it is also necessary to provide an extension for the cam plate 16, and to accomplish this a plate 20 provided with a cam or wedge 21 is provided, the said plate having a longitudinal slot 22 for engagement by a plurality of fastening devices 23 extending through and secured to the said lever, as shown clearly in Figure 8. It will thus be seen that provision is made for operating the prong-carrying bars 8 when disposed at different distances apart.

Secured to the rear side of the back wall of the hopper is a spacing block 24 to space the hopper from a wall or other support upon which it may be mounted in order to provide room for the placement of the sack and for engagement with and disengagement from the same by the rear prong-carrying bar 8. For supporting the hopper from a pair of nails or hooks or other devices projecting from a wall, a pair of hangers or strips 25 are secured to the rear side of the spacing block 24. For the support of the hopper from a portable support, a pair of reversed hooks 26 and 27 are secured to the rear side of said block, the

hooks projecting upward beyond the top of the block and of different dimensions for a purpose which hereinafter appears, and also secured to the rear face of said block is a guide frame or keeper 28 of U-shape, the same being arranged so that its arms shall fit against opposite sides of the portable support to guard against endwise rocking or shifting movement of the hopper. To provide for shortening the hopper, auxiliary end plates 29 are provided, the same having flanges 30 at their rear edges to fit flatly against the back wall of the hopper, and being provided at their lower ends with vertical hooks 31 to fit over the upper edge of the rear wall of the hopper, it being noted by reference to Figure 7 that the auxiliary end walls 29 converge downwardly much more sharply than the end walls 2 of the hopper and thus constrict or shorten the discharge opening thereof.

Referring now to the supports for the hopper as distinguished from the character of supports hereinbefore mentioned, namely nails, hooks or the like projecting from a wall or other fixed object, it will be noticed by reference particularly to Figures 5, 6 and 8, that the support is of channel form and is constructed as follows: 32 designates parallel angle bars connected together at suitable points by cross bolts 33 engaged by clamping nuts 34, sleeves 35 fitting on the cross bolts and spacing the bars apart. The channel frame thus constructed, is secured at its lower end upon a pair of fixed legs 36, and pivoted to and between said legs is a collapsible leg 37, the same being pivoted at 38. The leg 37 when in operative position, projects rearwardly and the legs 36 project divergently forward so as to leave the space clear below the hopper for the sack to be filled, and to secure the leg 37 in operative position, it is provided at its upper end with a wedge 39 for engagement by a sliding loop or keeper 40 mounted upon the channel. By sliding the keeper upwardly beyond the end of the wedge, the leg 37 can be folded toward the space between the legs 36 for convenience of storage.

The space between the angle bars 32 of the channel is adapted for the reception of either of the hooks 26 or 27, the former being the larger so that it may be hooked over any one of the sleeves 35, and also because of its extra length and shape it is suited to function with an extemporized support, as the end of an upright board, an auger hole in a partition, or a cleat secured to a wall.

For providing a yielding support for the hopper, the channel is increased in height, this being accomplished by bolting to its upper end an extension consisting of

a pair of angle bars 41, and the upper ends of said angle bars are connected by a cross piece 42 from which is suspended a retractile spring 43 attached at its lower end 5 to a slide bar or plate 44 fitting slidingly in the channel between bars 32 and the cross bolts 33 thereof, said slide bar or plate having a vertical series of openings 45 adapted for engagement by the hook 27, it 10 being understood that when the hopper is to be suspended from the spring supported slide plate, the hooks 26 and 27 are reversed so that the last named hook shall project rearwardly, and that when the hopper 15 is to be suspended from one of the cross bolts or sleeves 35, the hook 26 will be disposed rearwardly, it being apparent that the said hooks must be of different size because the plate 44 and the cross bolts and 20 sleeves are different distances from the front space of the channel, as shown most clearly by Figures 6 and 8. When a sack is to be yieldingly supported by the construction described, the hopper will be disposed initially 25 to hold the sack clear of the ground so that when filled to a sufficient degree, the spring will yield and permit the sack to rest upon the ground to take most of the weight off the sack, the retractile tendency 30 of the spring holding the unfilled portion of the sack in stretched or taut condition to facilitate the remainder of the filling operation.

In all of the figures of the drawings showing the prong-carrying bars, the latter appear in operative position, that is in the position they occupy when a sack is suspended from them. Before the sack is applied, they extend vertically downward and 40 the cam or wedge plate 16 occupies the position indicated by dotted lines in Figure 7. Assuming that the sack is fitted at its upper end over and outside the bars 8, the operator swings the lever inwardly and thus causes 45 its cam edges in line with the bars to engage the latter and swing them upwardly and outwardly to an angle at which the prongs will retain a sack, the said cam plate or wedge being retained between the bars through 50 engagement therewith of the squared ends 17^a of the said plate or wedge. Potatoes or other vegetables or objects are then poured into the hopper from the front side thereof and thence pass into the sack, the operation 55 described being the same regardless of how the hopper is supported. To disengage the sack from the prong-carrying bars, the lever is pulled outward, this action permitting the prong-carrying bars by gravity 60 to swing back to a vertical position and thus withdraw or partially withdraw their prongs from the sack to permit the same to be readily removed.

In both the rigid and yielding type of 65 standard, the points of attachment for the

hopper are numerous, giving in both designs a selective adjustment as to height to fit sacks of variable length.

From the above description it will be apparent that I have produced a sack holder 70 which embodies the features of advantage set forth as desirable in the statement of the objects of the invention, and which is obviously susceptible of modifications in various particulars without departing from 75 the principle of construction and mode of operation involved.

I claim:

1. A sack holder comprising a hopper having back and end walls, a pair of horizontal prong-equipped bars pivotally suspended from the hopper, and a wedge plate to be forced between and against said bars to swing them outwardly to dispose their prongs in position to impale and form 85 a suspension support for a sack.

2. A sack holder comprising a hopper having back and end walls, a pair of horizontal prong-equipped bars pivotally suspended from the hopper, and a wedge plate 90 to be forced between and against said bars to swing them outwardly to dispose their prongs in position to impale and form a suspension support for a sack; said plate having square ends paralleling and abutting 95 the bars to prevent them from swinging back to inoperative position.

3. A sack holder, comprising a hopper having back and end walls, a pair of horizontal prong-equipped bars pivotally suspended from the hopper, and pivoted means for rocking said bars to cause their prongs to impale a sack and form a support therefor; said means acting as a wedge to rock the bars apart and as a "chock" to stand 105 between the said bars to hold them in their adjusted position.

4. A sack holder, comprising a hopper having back and end walls, a pair of horizontal prong-equipped bars pivotally suspended from the hopper, a lever pivoted to one end of the hopper, and a plate having cam surfaces to engage and rock said bars upwardly and outwardly, and square ends to abut the inner sides of the bars to prevent them from swinging back to pivotally 110 pendent position.

5. A sack holder comprising an upright back, spaced horizontal prong-equipped bars pivotally suspended from the back and said bars respectively, end walls detachably suspended from the back and projecting forwardly therefrom, and means to rock between or withdraw from between said bars to swing them outwardly and upwardly 115 or permit them to return to their original positions.

6. A sack holder, comprising a hopper consisting of a back wall and downwardly converging end walls, bars projecting for- 120

wardly beyond and at the lower end of said end walls, a prong-carrying bar pivotally suspended from the said bars, a second prong-carrying bar pivotally suspended from the hopper at the rear side thereof, and a lever suspended from the hopper and provided with a cam plate or wedge for en-

gagement with and between adjacent ends of said bars for swinging the same upwardly and outwardly. ¹⁰

In witness whereof I hereunto affix my signature.

EDWIN TAYLOR.
